DESIGN FOR A CHARM BRACELET

Russell W. Grefe, Merrick, N. Y.

Application October 16, 1947, Serial No. 141,936

Term of patent 14 years

(Cl. D45—4)

To all whom it may concern:

Be it known that I, Russell W. Grefe, a citizen of the United States, residing at Merrick, Long Island, in the county of Nassau and State of New York, have invented a new, original, and ornamental Design for a Charm Bracelet, of which the following is a specification, reference being had to the accompanying drawing, forming a part thereof.

In the drawing:

Fig. 1 is a front elevational view of a charm bracelet, showing my new design; and

Fig. 2 is an enlarged vertical sectional view, taken on the line 2—2 of Fig. 1.

I claim:

The ornamental design for a charm bracelet, as shown.

RUSSELL W. GREFE.
